UNITED STATES PATENT OFFICE.

LAWRENCE S. VAN TASSEL, OF FINDLAY, OHIO.

WARM-AIR HEATER AND CIRCULATOR.

Application filed January 5, 1926. Serial No. 79,410.

This invention relates to heaters wherein the air is heated by means of gas jets or burners and particularly to a heater so constructed that the air of the room will circulate through the heater.

The general object of the invention is the provision of a warm air heater and circulator of such construction that the cold air will be taken from the floor and caused to circulate through the heater to thus properly warm the air and discharge it through the top of the heater, thus securing a complete circulation of the air.

A further object is to provide a heater so constructed as to secure a relatively large capacity for the circulation of air.

Still another object is to provide means whereby a view of the combustion chamber with the burners may be secured without the necessity of stooping down to look into the opening of the combustion chamber.

Other objects will appear in the course of the following description.

My invention is illustrated in the accompanying drawings, wherein:

Figure 1 is a vertical sectional view on the line 1—1 of Figure 3;

Fig. 2 is a vertical sectional view on the line 2—2 of Figure 1;

Fig. 3 is a cross section on the line 3—3 of Figure 2;

Fig. 4 is a section on line 4—4 of Figure 2; and

Fig. 5 is a section on the line 5—5 of Figure 3.

Referring to these drawings it will be seen that my heater consists of an outer shell or casing generally designated 10, which is approximately square or rectangular in cross section and is provided at its corners with hollow legs 11. This shell is formed of sheet metal, lined with asbestos 12, and with an inner layer of thin sheet metal, as for instance, tin, this layer being designated 13. At its upper end the outer shell with the lining layers is inwardly converged as at 14 and then extends upward and carries the screen or register 15, which may be made of any suitable open work material. The lower end of the shell 10 is open and the shell is formed of four panels of sheet metal riveted or otherwise engaged with the legs 11. These legs 11 extend downward below the shell as shown

in Figure 2, and are hollow as shown 55 in Figure 5. Riveted, brazed or otherwise attached to the legs is a frame or band 16 and inward of this band is a rectangular frame 17. The sheet metal of the panels forming the outer casing 10 extends down 60 between this outer frame 16 and the inner frame 17. This inner frame 17 has transversely extending elements 18. Extending around the upper portion of the casing or shell 10 and riveted, brazed or otherwise 65 attached to the upper ends of the legs 11 is a rectangular frame or band 19.

Disposed within the shell and resting upon the transversely extending members 18 is an octagonal casing 20 constituting the 70 outer wall of a combustion chamber. This octagonal wall 20 extends upward nearly the full height of the shell and this octagonal wall is provided with four openings, 21, preferably disposed so that the axes of said 75 openings are radial and extend toward the four legs, as shown in Figure 4. Mounted within the octagonal shell 20 and forming the inner wall of the combustion chamber is an air pipe 22 terminating at its upper end 80 in a relatively large air chamber 23. The air pipe 22 at its lower end is connected to the wall 20 by an angular web 24 while the upper end of the wall of the air chamber is connected to the octagonal wall 20 by the 85 web 25. Air flues 26 extend inward and upward from the openings 21 and communicate with the interior of the air chamber 23 as shown most clearly in Figures 2 and 5. Baffle plates 27 are attached to the wall 90 20 above these air flues 26, as shown in Figures 3 and 5, and act to deflect the air rising upward within the circulator into the air flues 26 and so into the air chamber 23. Disposed across the combustion chamber 95 28 is a web 29 constituting a baffle, this web at the front of the heater and circulator being cut away to form a semi-circular opening as at 30, see Figures 1 and 3. The upper portion of the combustion chamber 28 has a rearwardly extending flue 31 which extends out through the outer casing or shell, as shown in Figure 1. The rear of the casing at the lower end of the combustion chamber is formed with an inwardly extending passage 32. The baffle plate 29 directs the heat generated in the combustion chamber around the circulator

100
105

and then permits this heat to pass upward through the semi-circular opening 30 into the upper portion of the combustion chamber and then out through the flue 31. The 5 entire combustion chamber comprising the shell or wall 20 and the wall 22, the webs 24 and 25 and the connected air tubes 26, the flue 31 and the wall of the passage 32 are preferably welded into a single piece so 10 that there is no possibility of the escape of gas fumes. The air tubes 26, it will be noted in Figure 4, passing through the outer and the inner air chambers are placed opposite the corners of this cabinet heater and 15 circulator and are thus fed from the points of maximum air capacity in the inner chamber.

Disposed within the lower portion of the combustion chamber as shown in Figure 2, 20 are burners of any suitable character. I have illustrated these burners as being gas burners, designated 33. These burners are so formed as to discharge a jet of mingled gas and air upward and inward against the 25 air heating wall 22 of the air passage. These burners are connected by a pipe and T to a supply pipe 34 which extends out through the opening 32. I do not wish to be limited to the number of burners which 30 I may use, nor to the character of these burners and the showing made in the drawings is purely illustrative of the fact that I may use a plurality of gas burners disposed in the lower portion of the combustion 35 chamber.

Preferably I provide a mirror 35 pivotally mounted for adjustment around a pivot 36 and being held in its adjusted position by a thumb screw, wing nut or the like, and the mirror being disposed at such an angle that by looking directly down into the mirror, without stooping, it is possible to observe the condition of at least one of the 40 burners and thus see whether the flame is turned too high or too low or whether it needs adjustment.

The heater as described has an appearance very much like that of a phonograph cabinet and may be made more or less ornamental in 45 its character. The outer surface of the sheet metal constituting the outer shell may be enameled or otherwise finished to simulate fine woodwork if desired. The flue 31 will, of course, be connected to a stove pipe whereby the products of combustion may be carried off. It will be seen that this construction provides a very neat, simple and effective heater which takes relatively cold 50 air from a point adjacent the floor and carries it upward through the air pipe 22 and the air chamber 23 and through the space between the outer and inner shells, heats the air and then discharges it upward through the register 15. The air is directed 55 against the outside and inside faces of the

walls of the combustion chamber so as to receive a maximum of heating effect, and a portion of the air passing upward between the outside shell and the combustion chamber is deflected inward by the baffles 70 21, where it comes in contact with the direct heat from the burners and is then carried upward through the air chamber 23. The legs being hollow also provide means whereby air may be conveyed upward to be heated 75 and form part of the circulation system and at the same time these hollow legs have a maximum of strength with a minimum of weight. The legs extend downward and outward, as shown particularly in Figure 5, so 80 as to secure a firm base for the heater and circulator.

While I have illustrated certain details of construction and arrangement of parts which I have found particularly effective in 85 practice, I do not wish to be limited to all of these details as it is obvious that changes might be made therein without departing from the spirit of the invention as defined in the appended claims. 90

I claim:—

1. A heater and air circulator of the character described comprising an outer thin metallic shell having a register at its upper end and open at its lower end, legs supporting the said shell above the floor, a centrally disposed air chamber open at its upper and lower ends and terminating short of said register, a wall exterior to the air chamber and constituting the outer wall of a combustion chamber disposed outward of the air chamber, said combustion chamber having a smoke flue extending outward through the outer shell, a passage at its lower end extending through the outer shell, flues extending through the outer wall of the combustion chamber and opening into the interior of the air chamber, baffles disposed above the entrance ends of said flues, and a baffle disposed within the combustion 100 chamber above said flues and separating the combustion chamber into two sections and said baffle at a point diametrically opposite to the smoke flue being provided with an opening. 110

2. An air circulator and heater comprising an outer shell, rectangular in cross section and formed of thin metal panels, the panels being joined at their edges by upwardly extending legs, a central air circulator disposed within the hollow shell and open at its upper and lower ends, a wall exterior to the air chamber and spaced from said shell and defining a combustion chamber immediately surrounding the air chamber, the upper portion of the combustion chamber being separated from the lower portion by a baffle wall having an opening at the front of the heater, said combustion chamber at its rear having an outwardly extending 120 125 130

smoke flue disposed above the baffle and extending through the outer shell and at its lower end having an entrance passage extending through the outer shell, the space 5 between the outer shell of the combustion chamber being connected to the interior of the air chamber by means of upwardly in-

clined air flues and said flues being disposed with their axes directed to the corners of the outer shell. 10

In testimony whereof I hereunto affix my signature.

LAWRENCE S. VAN TASSEL.
